[57] **CLAIM**

The ornamental design for an exerciser for attachment
to door or the like, as shown and described.

DESCRIPTION

FIG. 1 is a perspective view of an exerciser for attach-
ment to door or the like showing my new design;

FIG. 2 is a bottom plan view thereof;

FIG. 3 is a right side elevational view thereof, the side
opposite being substantially a mirror image;

FIG. 4 is a perspective view of a modified form of the
design shown in FIGS. 1 through 3;

FIG. 5 is a bottom plan view thereof; and

FIG. 6 is a right side elevational view thereof, the side
opposite being substantially a mirror image.

FIG. 1

FIG. 2

FIG. 3

FIG. 4
